(57) **CLAIM**

The ornamental design for a wire controller, as shown and described.

DESCRIPTION

FIG. 1 is a front bottom perspective view of a wire controller of the present disclosure according to one embodiment; FIG. 2 is a front top perspective view of the wire controller shown in FIG. 1; FIG. 3 is a front elevational view of the wire controller shown in FIG. 1; FIG. 4 is a rear elevational view of the wire controller shown in FIG. 1; FIG. 5 is a left-side elevational view of the wire controller shown in FIG. 1; FIG. 6 is a right-side elevational view of the wire controller shown in FIG. 1; FIG. 7 is a top plan view of the wire controller shown in FIG. 1; FIG. 8 is a bottom plan view of the wire controller shown in FIG. 1; FIG. 9 is a front bottom perspective view of a wire controller of the present disclosure according to another embodiment; FIG. 10 is a front top perspective view of the wire controller shown in FIG. 9;

FIG. 11 is a front elevational view of the wire controller shown in FIG. 9; FIG. 12 is a rear elevational view of the wire controller shown in FIG. 9; FIG. 13 is a left-side elevational view of the wire controller shown in FIG. 9; FIG. 14 is a right-side elevational view of the wire controller shown in FIG. 9; FIG. 15 is a top plan view of the wire controller shown in FIG. 9; and, FIG. 16 is a bottom plan view of the wire controller shown in FIG. 9.

(Continued)

The broken lines shown in the drawings are for the purpose of illustrating portions of the wire controller that form no part of the claimed design.
